US00D550836S

(12) **United States Design Patent** (10) **Patent No.:** **US D550,836 S**
Chandran et al. (45) **Date of Patent:** **** Sep. 11, 2007**

(54) **VENTILATION INTERFACE**

(75) Inventors: **Sanjay Chandran**, Boca Raton, FL (US); **Shara Hernandez**, Davie, FL (US); **Louis Javier Collazo**, Atlanta, GA (US)

4,312,359 A 1/1982 Olson
4,367,735 A 1/1983 Dali
4,367,816 A 1/1983 Wilkes
4,406,283 A 9/1983 Bir
4,422,456 A 12/1983 Teip

(Continued)

(73) Assignee: **RespCare, Inc.**, Coconut Creek, FL (US)

FOREIGN PATENT DOCUMENTS

DE 146688 2/1981

(Continued)

(**) Term: **14 Years**

(21) Appl. No.: **29/245,378**

(22) Filed: **Dec. 23, 2005**

FIG. 1 is a top and right front perspective view of a ventilation interface, showing our design;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.
